(57) **CLAIM**

The ornamental design for a storage box as shown and described.

DESCRIPTION

FIG. 1 is a top, front, right side perspective view of a storage box showing the new design;

FIG. 2 is a front view thereof;

FIG. 3 is a rear view thereof;

FIG. 4 is a left side view thereof;

FIG. 5 is a right side view thereof; and,

FIG. 6 is a top side view thereof.

Lightly shaded portions of the storage box in FIGS. 1-5 form no part of the claimed design.

1 Claim, 6 Drawing Sheets
